UNITED STATES PATENT OFFICE.

WILLIAM H. GALLUP, OF TROY, NEW YORK, ASSIGNOR TO THE GALLUP NOVELTY WORKS, OF SAME PLACE.

SHOW-STAND FOR COLLARS AND CUFFS.

SPECIFICATION forming part of Letters Patent No. 373,823, dated November 29, 1887.

Application filed June 27, 1887. Serial No. 242,614. (No model.)

To all whom it may concern:

Be it known that I, WILLIAM H. GALLUP, of the city of Troy, county of Rensselaer, and State of New York, have invented a new and useful Device for Displaying Collars and Cuffs, of which the following is a specification.

My invention relates to an apparatus for holding and displaying collars and cuffs when the latter by samples are exhibited for sale; and my invention consists (as will be more fully detailed hereinafter in connection with its illustration) in the combination, with a standard-support, of a series of bracket-wires having on their outer ends a support for an apparel collar and cuff, and on their inner ends said bracket-wires being attached to the standard, with the latter pivotally connected with a base.

My invention also consists, as will be detailed hereinafter in the claims, in the sub-combination of the parts where they perform specific function.

Accompanying this specification, to form a part of it, there are four plates of drawings containing eight figures illustrating my invention, with the same designation of parts by letter reference used in all of them.

Of the illustrations, Figure 1 shows a side elevation of a standard-support containing two of my devices for displaying collars and cuffs. Fig. 2 shows a view of the standard-plate, in which the ends of the brackets supporting the collar and cuff frame are inserted, said plate being shown in larger proportion than at Fig. 1. Fig. 3 shows one of the bracket-wires illustrated as detached from the standard-plate. Fig. 4 shows in side elevation the collar-frame and cuff-support as detached from the bracket-wire. Fig. 5 shows a collar and cuff applied to said frame. Fig. 6 shows the frame as illustrated at Fig. 4, but as having added thereto wire loops to support and spread out the capes of a woman's collar when such a collar is applied thereto. Fig. 7 shows in side elevation a collar having a cape and a cuff arranged on the frame that is shown at Fig. 6, with the vertical cuff-supports and the cape-loop supports designated by dotted lines. Fig. 8 shows the completed stand.

The several parts of the apparatus thus

illustrated are designated by letter reference, and the function of the parts is described as follows:

The letter S indicates a standard-support provided with a series of encircling plates, p' . 55 These plates are punctured, as shown at O, to receive the inner ends of the S-form bracket-wires W. This standard is made in two parts, $S^1 S^2$, the lower standard part, S^1 , being adapted to have the upper standard part, S^2 , enter 60 it telescopically, and to rest therein upon the lower base-plate, p'' , and thus make a pivotal connection therat.

The letter F designates a collar-frame having a hoop form made to consist of a band, b' , 65 that is on its inner face, by means of radially-arranged wires w^2 , connected to the socket-tube T, the latter having on its under side a tubular opening, O^2 , adapted to receive the outer end of the S-form bracket-wire W, by 70 which the frame is attached to or detached from said bracket-wire. The letter b^2 designates a pin or button projected from the side of said frame to attach the front ends of the collar therat, and b^3 a pin and button at the 75 opposite side of said frame for buttoning thereon the back of the collar.

The letters $L^1 L^2$ designate wire cape-loops that are downwardly and outwardly projected from the band of the collar-frame F, the function of which is to spread out and keep in place the capes of women's collars when the frame is used to display and show the latter class of goods.

The letters C C C designate cuff-supports, 85 which are made of wire, and which at their lower ends are attached to the inner sides of the frame F, and therefrom extended inwardly and then vertically and slightly outwardly to bend inwardly at the top in such a manner as 90 to make them press elastically outward after they have been forced inwardly to have a cuff placed around them, as shown at Figs. 4 and 7.

The letter R indicates rests or supports that are outwardly projected from the bottom of 95 the band b' for the lower edge of the collar to rest upon.

The letters N designate wire studs that are upwardly projected from the frame F, with the upper ends of said studs having coils heli- 100

cally made therein, and thus adapted to receive cards containing cost-marks there held in place by being pressed in between the coils.

As thus constructed, the combined **S**-form bracket, as adapted to connect with a standard-support when combined with the frame F, is by means of the buttons on the band b' adapted to have placed thereon a man's collar with the latter displayed in the position it has when worn, and when the said band b' is combined with the loops L² L² the device may be used to display a woman's collar in the position it has when worn and with the capes spread out. Any number of these bracket-wires and frames that it is convenient to use may be applied to a standard-support, and thus a large number of differing styles of collars and cuffs may be shown and displayed at once.

Having thus described my invention, what I claim, and desire to secure by Letters Patent, is—

1. The combination, with the **S**-form bracket-wire W, adapted at one of its ends to connect with a standard-support, of the frame F, made with the hoop-form band b', provided with buttoning attachments oppositely arranged thereon, and a centrally-arranged socket adapted to receive the outer end of said bracket-wire, substantially in the manner as and for the purposes set forth.

2. The combination, with the **S**-form bracket-wire W, that at one of its ends is adapted to attach to a standard-support, of the frame F, made with the hoop-form band b', that has oppositely-arranged buttoning devices, said frame being provided with a socket to receive the outer end of the bracket-wire, and cape-loops L² L², attached to said band, substantially in the manner as and for the purposes set forth.

3. The combination, with the **S**-form bracket-wire W, adapted at one of its ends to attach to a standard-support, of the frame F, made with the hoop-form band b', and having buttoning

devices oppositely arranged thereon, said frame having a socket to receive the outer end of said bracket-wire, and being constructed with the cuff-stud supports C C C, connected to said frame, arranged substantially in the manner as and for the purposes set forth.

4. The combination, with the **S**-form bracket-wire W, adapted to connect at one of its ends with a standard-support, of the frame F, made with the band b', having buttons oppositely arranged thereon, and the rests or supports R, arranged on the lower edge of said band, substantially as and for the purposes set forth.

5. The combination, with the **S**-form bracket-wire W, adapted to connect at one of its ends with a standard-support, of the frame F, made with the hoop-form band b', having the supports R arranged thereon, and oppositely-placed buttoning devices, and the wires N, constructed at their upper ends with helical coils, said wires being upwardly projected from said frame, substantially as and for the purposes set forth.

6. The combination, with a standard-support made in two parts and having a pivotal connection in which the upper part of said standard may turn, of the plates p', arranged on the upper part of said standard, the **S**-form brackets W, each arranged upon their inner ends to connect with one of said plates, the frame F, arranged on the outer ends of each of said bracket-wires, the band b', constructed with oppositely-arranged buttoning devices and arranged on each of said frames, substantially in the manner as and for the purposes set forth.

Signed at Troy, New York, this 5th day of May, 1887, and in the presence of two witnesses whose names are hereto written.

WM. H. GALLUP.
